LOUIS E. BALTZLEY, OF GLEN RIDGE, NEW JERSEY

ELECTRIC CONNECTER

Application filed March 17, 1928. Serial No. 262,433.

This invention relates particularly to quick detachably connecters of the cord plug type, in which separation can be effected by a pull on the cord. The detachment of the 5 plug in this fashion places a strain on the electrical conductors, tends to loosen the binding posts and in some cases results in injury to the receptacle or other apparatus with which the plug is connected.

10 Special objects of the invention are to overcome these objections and to make it possible to quickly and positively effect the separation of the plug from the companion circuit member without straining the parts and, 15 in the case of portable apparatus, such as an electric percolator, pressing iron or the like, by a single handed operation and without disturbing or displacing such apparatus.

The foregoing and other desirable objects 20 are attained by certain novel features of construction, combinations and relations of parts, as illustrated in the accompanying drawing and broadly covered in the following specification and claims.

25 In the drawing several different embodiments of the invention are illustrated, but it will be understood that the structure may be modified and changed without departure from the true spirit and basic scope of the invention.

Figure 1 is a plan and part sectional view of a form of the invention embodied in a plug such as used with an electric coffee percolator or the like.

30 Figure 2 is a sectional view as on line 5—5 of Figure 1, illustrating the ejector or separator in the position it occupies after effecting separation.

Figure 3 is a part sectional view taken as 40 on the central line of separation of the plug and illustrating the thrust piece in the form of a sliding ribbon guided in a curved path between the upper and lower members of the plug body.

45 Figure 4 is a sectional view of the latter form of plug, as on substantially the plane of line 8—8 of Figure 3, with the separator projected in the act of thrusting the plug away from the member with which it cooperates.

50 The plugs illustrated in Figures 1 to 4 are

of the type employed with electric percolators and the like and are shown as made up of companion insulating base sections 23 secured together by screws 24 and containing spring contact socket members 25, 26, set in 55 correspondingly shaped recesses 27 between the insulating blocks in position to receive the projecting contact pins 28 on the percolator or other electrical device 29 which forms the companion connecting element of 60 the plug.

In these particular forms of the invention, the separating means is made in two parts, positioned to act against the contact pins of the other member of the coupling 65 and actuated by push buttons positioned to be gripped between a thumb and finger of one hand.

The separating devices shown in Figures 1 and 2 consist of narrow blades or bars 30 70 of generally triangular shape, each pivoted in one corner on a pin 31 and having one end projecting inwardly with a rounded cam surface 32 to engage the tip of the contact pin and a shorter arm 33 slidingly engaging a slot 34 in the head 35 at the inner end of a push button 36. These push buttons project from opposite sides of the plug, being guided in cooperating concavities 37 formed in the meeting faces of the blocks. The separating 75 levers 30 are similarly guided in flat cooperating recesses 38 in the opposing faces of the blocks and the pivot pins 31 may simply be loose pins extending through the levers into seats formed in the opposing faces of 80 the blocks.

The pin ejecting arm of the lever is guided and at the same time frictionally retained in position by extending in between the two 85 spring socket members 25, 26 of the contact. 90 As the plug is engaged with the member with which it is designed to cooperate, it will be seen that the contact pins will push back the separating levers into the position indicated in Figure 1 with the push buttons fully 95 exposed at the sides of the plug and that to separate the plug it is simply necessary to pinch the push buttons together between the thumb and forefinger of one hand, this action 100 rocking the levers and causing them by en-

gagement with the ends of the pins to positively push the plug away from the other member of the circuit.

In the form of the invention shown in Figures 3 and 4, the separating members are in the form of ribbons or strips 39, working in curvilinear guide slots 40, extending inwardly from opposite sides of the plug and thence longitudinally so as to bring the ends 10 of the ribbons into engagement with the ends of the contact pins. The curve of these guide slots is relatively gradual so that the lateral motion of the push buttons is translated into a longitudinal movement at the inner ends of 15 the strips or slides without binding or excess friction. These strips are closely confined in the guide slots and so can be made of light flexible material, either metallic or insulating material. The push buttons are preferably 20 made of insulating material.

The contacts shown in Figures 3 and 4 are of special form in that the blade portion of each spring contact 41 is split longitudinally at 42 and slotted longitudinally at 43 to provide 25 spring contact tongues 44 for gripping the contact pins each at four different substantially equally spaced points or lines of contact. The slots 42 also provide a passage-way for the inner ends of the strips or flexible 30 plungers. The intermediate curved portions of these plungers are longitudinally slotted as indicated at 45 to receive the base or shank portions of the contacts 41.

In the described forms of the invention, 35 the separating mechanism is entirely housed within the plug structure and can be incorporated in the plug, without materially adding to the weight or bulk of the plug. The parts also are quite inexpensive and easily 40 assembled. In the form shown in Figures 1 and 2, where the separating arm of the thrust lever slides between the opposing socket contacts, said contacts are kept clean and bright by such wiping action.

45 The opposed push buttons provide a convenient grip for handling the plug and as they sink into the sides of the plug, let the fingers which actuate them, come to rest against the solid side portions of the plug.

50 What is claimed is:

1. In electric connectors, a plug having cord terminals and contacts, substantially oppositely disposed actuators on said plug and means operated thereby to positively shift 55 said plug away from a companion member with which the plug is engageable.

2. A cord terminal plug having a circuit contact, a plug shifting lever pivoted in said plug to exert thrust in one direction against 60 part of a cooperating member with which the plug may be engaged and a push button operating at an angle to the direction of thrust of said lever for positively operating said lever to thrust said plug away from the member 65 with which it cooperates.

3. As a new article of manufacture, an electric connector plug body, a manually operable push button guided for movement in said plug body, a separator mounted in the plug body for operation by said push button and a contact mounted in the plug body and guiding said separator for movement in a direction to exert a separating thrust against a portion of a member with which said connector plug is designed to cooperate. 70

4. As an article of manufacture, an electric connector plug having a separator movably mounted therein and provided with external operating means and a contact in the plug having a guiding engagement with said separator and directing said separator in a line of travel to exert a separating thrust against a portion of a member with which the plug is intended to cooperate. 80

5. As a new article of manufacture, an electric connector plug having an exposed push button, an ejector operating within the plug and positioned to be actuated by said push button and a contact in the plug guiding said ejector to exert a separating thrust against a portion of a member with which the plug is designed to cooperate. 85

6. As a new article of manufacture, an electric connector plug having push buttons exposed at opposite sides of the same in position to be pinched between the fingers of one hand and plug separating means actuated by said push buttons to exert a separating thrust against a portion of a companion member to which the plug is intended to be coupled. 90

7. In apparatus of the character disclosed, the combination with a member having a contact and a detachable plug member having a companion contact and separating means carried by said plug member positioned and operating in said plug member to exert a positive separating thrust against the contact of the first member to effect separation of the plug from said first member. 105

8. In apparatus of the character disclosed, a member having pin contacts, a detachable plug having sockets to receive said pin contacts and carrying cooperating contacts in said sockets and plug separating means positioned and operating in the plug member to exert a positive endwise separating thrust against the pin contacts when the latter are entered in the sockets of the plug. 110

9. In apparatus of the character disclosed, a member having pin contacts; a detachable plug having sockets to receive said pin contacts and carrying cooperating contacts in said sockets and plug separating means positioned and operating in the plug to engage the pin contacts when the latter are entered 115 in the sockets of the plug and exposed push buttons on the plug for actuating said plug separating means. 120

10. A detachable cord plug having electric contact means for engagement with compa- 125

ion contact means of a member with which said plug is designed to cooperate, a separator operable in the plug to exert a longitudinal thrust against a portion of said cooperating member and transversely operable grip devices projecting at opposite sides of the plug and connected to operate said longitudinally thrusting separating means and thereby enabling the separation of the plug to be effected by a transverse pinching force such as would be exerted by the fingers of a hand encircling the plug.

11. A detachable cord plug having electric contact means for engagement with companion contact means of a member with which said plug is designed to cooperate, a separator operable in the plug to exert a longitudinal thrust against a portion of said cooperating member and transversely operable grip devices projecting at opposite sides of the plug and connected to operate said longitudinally thrusting separating means thereby enabling the separation of the plug to be effected by a transverse pinching force such as would be exerted by the fingers of a hand encircling the plug, said separating means being guided and housed within the plug at all times, the plug having a contact socket to receive a projecting contact of the cooperating device and said ejecting means being guided for movement in line with said contact socket to thereby engage a projecting contact entered in said contact socket.

12. In combination with an electrical device having a projecting contact, a separable connector plug socketed to receive said projecting contact and having a contact element to cooperatively engage the projecting contact when the latter is entered in the socket of the plug, a separator guided in the plug for engagement with the projecting contact when the latter is entered in the plug socket and exposed operating means for said separator.

13. In combination with an electrical device, having projecting contact pins, a separable connector plug socketed to engage over said contact pins and having contact elements to cooperate with said pins, movable separator means guided in the plug to engage the ends of said contact pins when the latter are entered in the plug and exposed actuating means for said separator means.

14. In combination with an electrical device having a projecting contact, a separable connector plug socketed to receive said projecting contact and having a contact element to cooperatively engage the projecting contact when the latter is entered in the socket of the plug, a separator guided in the plug for engagement with the projecting contact when the latter is entered in the plug socket and exposed operating means for said separator, said separator including a rocking lever pivoted in the plug and angled to con-

vert a transverse movement thereon into a longitudinal thrust against the projecting contact.

15. In combination with an electrical device, having projecting contact pins, a separable connector plug socketed to engage over said contact pins and having contact elements to cooperate with said pins, movable separator means guided in the plug to engage the ends of said contact pins when the latter are entered in the plug and exposed actuating means for said separator means, said ejector means including rocking levers pivoted in the plug and angled to convert transverse movements thereon into longitudinal thrust movements against the contact ends.

16. A separable connector plug, comprising a plug body having contacts for engagement with cooperating contacts of an electrical device and angled levers pivoted in said plug body and provided with finger pieces at their outer ends and adapted to exert longitudinal separating thrusts at their inner ends.

In testimony whereof I affix my signature.
